(57) **CLAIM**

The ornamental design for a magnetic clothing clasp, as shown and described.

DESCRIPTION

FIG. 1 is a perspective front right side view of the magnetic clothing clasp showing my new design;

FIG. 2 is a perspective back left side view thereof;

FIG. 3 is a front side view thereof;

FIG. 4 is a back side view thereof;

FIG. 5 is a left side view thereof;

FIG. 6 is a right side view thereof;

FIG. 7 is a top side view thereof; and,

FIG. 8 is a bottom side view thereof.

FIG. 9 is a perspective front right side view in the closed position; and,

FIG. 10 is a perspective back left side view thereof.

The dashed lines indicate boundary areas and form no part of the claimed design.
